O 12,328

UNITED STATES PATENT OFFICE.

THOMAS J. STEARNS, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 12,328, dated June 21, 1881.

Application filed May 3, 1881. Term of patent 3½ years.

To all whom it may concern:

Be it known that I, THOMAS J. STEARNS, of Boston, in the county of Suffolk and State of Massachusetts, have invented a certain new and original Design for Carpets, of which the following is a specification.

My present design is fully shown in the accompanying photographic illustration, forming part of this specification.

The design is composed of the following elements, viz: The figures A, (representing a blooming plant in a vase,) arranged alternately in parallel rows, the ornamented geometrical figures B, the irregular figures C, the figures

D, (representing urns or vases,) the lotus-flower 15 ornamentation E, the detached borders G and H, and the figures J, all disposed as shown.

I claim—

The design for a carpet, substantially as shown and described. 20

In testimony whereof I have signed my name to this specification, in the presence of two subscribing witnesses, this 28th day of April, A. D. 1881.

THOMAS J. STEARNS.

Witnesses:
